[57] ABSTRACT

The invention relates to a submersible caisson adapted for use in the construction of sea or river works, of the kind comprising a bottom, at least one lateral wall and a dividing-up device for liquid ballast forming a cellular structure in section substantially parallel to said bottom. The said dividing-up device is a structure completely independent of the wall and the bottom of the caisson which can thus be calculated precisely in accordance with the applied stresses.

Many alternative forms of construction are given and the applications referred to are fluid-storage reservoirs, dykes, breakwaters, quay walls, lock walls, dam elements, etc.

SUBMERSIBLE CAISSENS AND THEIR APPLICATIONS

The present invention relates generally to sinkable or submersible caissons capable of use in the construction of sea or river water-works and is also directed to the sea or river water-works built by means of such caissons.

The sinkable caissons utilized at the present time for sea or river works generally comprise a bottom and a lateral wall, and it is usual to provide them with a partitioning system forming a cellular structure in section substantially parallel to said bottom.

This partitioning arrangement has generally a double purpose, namely on the one hand to reinforce the actual structure of the caisson, and on the other hand to divide or split-up the liquid ballast which pours into the caisson, thereby ensuring it suitable static and dynamic stability in the vicinity of a given position of trim, known as the normal trim, especially during its placing in position.

In the constructional techniques known at the present time, this partitioning device is incorporated in the caisson, which may offer the advantage of simplicity but which presents the disadvantage that it does not dissociate the two functions which it carries out.

The result of this is especially that the actual wall of the caisson is required to withstand forces which are practically of the same order as those of the partitioning system, that it is practically impossible to employ a relatively thin wall for the caisson in view of the forces introduced into this wall by the partitioning system which is fixed in it here and there, and that it is finally difficult to adapt the thickness of these elements correctly to the forces which are applied to it at a given depth of immersion.

These drawbacks become increasingly important as the depth of submersion of the caisson considered increases.

There have of course been proposed various types of special caissons complying with various specific requirements.

Some of these special caissons, intended to form the walls of quays are designed in such manner as to be capable of being tilted on the float-line before they are submerged. They have a relatively complex structure with an inclined rear face formed by a large number of arches.

Other special caissons are more particularly designed in order to form under-water tanks to be submerged to great depths.

Finally, other special caissons are made of cylinders joined together, each having as its bottom a thin dome capable of being eliminated after submerging, by means of explosive charges.

The common feature of all these special caissons is that they have the drawbacks briefly specified above, essentially due to the fact that their partitioning system forms an integral part of the caisson.

The present invention has generally speaking for its object to overcome this drawback.

More precisely, it has first of all for its object a sinkable caisson for sea or river water-works of the kind comprising a bottom, at least one lateral wall and a device for dividing-up the liquid ballast, forming a cellular structure in section substantially parallel to the said bottom, characterized in that the said dividing-up de-

vice is is a structure independent of the said wall and of the said bottom.

It has also for its object a dividing device of this kind, taken separately.

It has finally for its object a sea or river water-works of any kind comprising at least one sinkable caisson utilizing or having utilized a dividing device of this type.

The dividing-up system according to the invention forms a structure entirely separate from that of the caisson, and thus it does not introduce into the walls of this latter any forces or stresses other than those resulting directly from the presence of a liquid ballast in the interior of this partitioning system. The thickness of the caisson walls can then be calculated very accurately and can in the majority of cases be substantially reduced as compared with the thickness of comparable sinkable caissons known at the present time.

In addition, the partitioning device according to the invention being independent of the caisson in which it is fitted, it may be removable and if so desired could be recovered for a fresh use.

In most cases, it is however sufficiently cheap to be abandoned, if so desired in the final work constituted by the caisson when this latter is in position.

Furthermore, the partitioning device according to the invention has generally only a low weight and it therefore only raises very little the centre of gravity of the caisson in which it is installed. It may thus occupy in such a caisson only a substantially lower height than in comparable sinkable caissons known at the present time, this height being measured from the bottom of the caisson.

In addition, the dividing-up arrangement according to the invention does not interfere in any substantial manner with the play of the thrust and abutment forces on the lateral wall of the caisson of the final ballast, generally of sand, which ensures its stability after submersion.

Furthermore, the dividing-up arrangement according to the invention renders possible the construction of cylindrical caissons, the wall of which is only coupled to the associated bottom by anisotropic means, such as hooped synthetic rubber supports, preferably in combination in this case with flexible fluid-tight sealing means.

The dividing-up device according to the invention also makes it possible to produce caissons the lateral wall of which is, over at least part of its height, doubled by a second wall which is associated with the same bottom as the first, but which is quite free of any mechanical coupling with the first, the annular space thus formed permitting for example the placing in position of a final ballast, and ensuring in all cases an improved protection of the caisson against possible shocks.

Other advantages result from the fact that the caisson, which may especially be made of pre-stressed reinforced concrete, is free at its final stage from any rigid internal partitioning, which for example facilitates the placing in position of the final ballast, after submerging.

However this may be, the dividing-up device according to the invention may be presented in numerous forms of construction.

It may for example bear directly against the walls or the bottom of the caisson.

In an alternative form, it may only bear on the wall and/or the bottom of the caisson by a lattice network of rolls radially deformable under pressure.

In all cases, the device has preferably relative deformability with respect to the wall of the caisson, such that the pressure of a liquid ballast contained therein is transmitted in a substantially uniform manner to the said wall.

In a simplified form, the dividing-up device according to the invention may be formed by an assembly of partitions which are substantially perpendicular to the bottom of the caisson, and which plunge into a relatively impermeable bed of material resting on the said bottom.

In addition, according to another aspect, the dividing-up device according to the invention may be in one piece or it may be composed of a number of distinct parts separable from each other.

As has been mentioned above, the present invention has also for its object a sea or river water-works comprising at least one submersible caisson of the type briefly described above.

It may be concerned, for example, with a fluid storage reservoir, an embankment, a breakwater, a quay wall, a side wall of a lock, a dam element, etc.

More particularly, in the case of a fluid storage reservoir, the wall of this reservoir is preferably formed by an upward extension of the wall of a submerged caisson of the type such as briefly described above, and its bottom is preferably formed by a flexible fluid-tight layer resting on a sandy ballast placed on the bottom of the said caisson.

Reservoirs of this kind enable the product which is stocked in them to be kept out of direct reach of a shock damaging their supporting structure.

They may furthermore be utilized under the same conditions as a land reservoir of the same capacity, especially as regards the pumping of the product stored.

In addition, they may be equipped with a conventional floating roof.

In the case of a breakwater, this may comprise according to the invention a plurality of similar sinkable caissons located at a distance from each other.

The cylindrical shape of these caissons, combined with the empty spaces existing between them, generally permits an effective damping of the swell in a very open sector centered on a perpendicular to the work constituted by such an association of caissons, while limiting the amplitude of the ripple complex in front of a work of this kind to a value definitely lower than that of the normal lapping amplitude.

The characteristic features and advantages of the invention will further be brought out in the description which follows below, given by way of example, reference being made to the accompanying diagrammatic drawings, in which:

FIG. 1 is a view in vertical section of a caisson according to the invention during the course of its submersion, this cross-section being taken along the line I—I of FIG. 2;

FIG. 2 is a view in transverse section of this caisson, taken along the line II—II of FIG. 1;

FIG. 3 is a view on a larger scale in partial cross-section of this caisson, taken along the line III—III of FIG. 2.

FIG. 4 is a view similar to FIG. 2, and relates to an alternative form of construction;

FIGS. 5 to 8 are partial views in vertical cross-section of this alternative form, taken respectively along the lines V—V to VIII—VIII;

FIG. 9 is a view similar to FIG. 8 and illustrates a working phase of the partitioning device according to the invention;

FIG. 10 is a view in vertical cross-section illustrating the placing in position by immersion of a caisson according to the invention;

FIG. 11 is a view in vertical cross-section of a storage reservoir formed by means of a caisson of this kind;

FIG. 12 is a partial view to a larger scale and in vertical cross-section of this reservoir;

FIG. 13 is a view in elevation and in cross-section illustrating an installation comprising a number of these reservoirs;

FIG. 14 is a plan view of an installation of this kind;

FIG. 15 is a view in vertical cross-section of a simplified form of construction of a partitioning device according to the invention;

FIG. 16 is a view in partial axial cross-section to a larger scale of a caisson according to the invention;

FIG. 17 is a partial view in transverse cross-section of this caisson, taken along the line XVII—XVII of FIG. 16;

FIG. 18 is a view similar to FIG. 16 and relates to an alternative form of construction;

FIG. 19 is a view similar to FIG. 15 and concerns an alternative form of construction;

FIG. 20 is a view of this alternative form in cross-section taken along the line XX—XX of FIG. 19;

and FIG. 21 is a view similar to FIG. 12 and relating to another alternative form of construction.

FIGS. 1 and 2 relate to a caisson comprising generally a bottom 10 and a cylindrical lateral wall 11. In the example shown, the transverse section of this caisson is square and the thickness of its wall 11 decreases gradually from its bottom.

According to the invention, with this caisson is associated an internal dividing-up system 12, formed by a plurality of partitions 13 substantially perpendicular to the bottom 10, the said partitions 13 forming in section parallel to this bottom a cellular structure.

Each of the cells 14 of this structure is fluid-tight with respect to the adjacent cells.

According to the form of construction shown, the partitions 13 which form these cells are incorporated in a common bottom 15, and the dividing-up device 12 thus constituted only bears against the bottom 10 and the wall 11 of the caisson by means of a lattice system of rolls 16.

These rolls or tubes 16 are preferably inflatable, is so desired, by independent sections, from an inflation system 17.

These rolls 16 are formed by radially deformable casings which are substantially inextensible. In FIG. 2 their crossing has been shown level with a junction of the cellular structure constituted by the partitioning device 12.

The rolls or tubes 16 have a double purpose. On the one hand they ensure a contact between the dividing-up device 12 and the caisson, and on the other hand, they divide-up the space existing between these elements in order to minimize the movements of the ballast water in this space with respect to the period of oscillation of the whole unit.

However this may be, it is important that the dividing-up device 12 should not have any considerable movement with respect to the caisson, which could give rise locally to excess pressures liable to effect this latter

adversely. It is also important that the levels of ballast water in each of the cells 14 of the dividing-up device 12 do not differ from each other, for the whole of the cells, by more than a height lower than a previously fixed limit, the actual strength of the partitions 13 of this dividing-up device being calculated as a function of this limit.

The rolls or tubes 16 inherently act in opposition to any movement of the dividing-up device 12 with respect to the caisson, but in an alternative construction this function could be effected by any appropriate fixing means, and for example by means of tenons which fix together the bottoms 10 and 15.

As regards the levels in the cells 14, in order to control them, there may be available at the base of each wall or partition 13 of the dividing-up device, two clapper-valves working in opposite directions from one cell 14 to the adjacent cell, the said clapper-valves or other one-way flow devices (not shown) being calibrated or set in such manner as to operate when the difference in pressure between the cells in question reaches a predetermined value, taking account of suitable coefficients of safety.

In practice, the rolls 16 are inflated to a pressure higher than that which will be applied to them by the liquid ballast placed in position in the dividing-up device 12 during the immersion of the caisson.

These rolls 16 thus transmit to the caisson only the forces which are directly associated with the mass of this ballast.

As will be readily understood, and as shown in FIG. 1, this ballast gradually introduced into the dividing-up device 12 permits the progressive placing in position of the caisson up to its immersion, the dividing-up device 12 permitting a suitable trim of the said caisson to be maintained by partitioning this ballast.

Once the caisson has been sunk, the dividing-up device may be eliminated if so desired and it may eventually be recovered for a fresh use.

According to the alternative construction illustrated in FIGS. 4 to 7 and more particularly intended for cylindrical caissons of large size and circular section, the dividing-up device 12 according to the invention rests on a bed of sand 20 which forms a ballast ensuring a good stability of the bottom of the caisson on the water-line, without ballast, and several similar portions 21 are formed six in number in the example shown, these having generally the form of circular segments.

The portions 21 are separable from each other and are movable.

These portions 21 have as before a cellular structure and are arranged around a central well 22. This well is provided with a cover 23 which also ensures the central junction of the said portions 21.

As can better be seen from FIG. 6, the upper adjacent edges of two adjacent portions 21 are covered in pairs by a joint cover 25.

On the periphery, the dividing-up device 12 is coupled to the cylindrical wall 11 of the caisson by two flexible skirts, one 28 coming from the upper edge of the portions 21 and held applied against the wall 11 of the caisson by an inflatable circular tube 29, or any other device, the other, 30, coming from the base of the portions 21, and being applied against the wall 11 of the caisson by the liquid ballast introduced into the dividing-up device 12.

The flexible skirt 30 forms with the peripheral cells 13, an annular space which is partitioned and which communicates with the said peripheral cells by passages 26 located at the base of the corresponding walls 13.

Similarly, around the well 22, the end cells 27 of the portions 21 communicate with the adjacent cells by similar passages 26.

As will be readily understood, the flexible skirt 28 10 prevents any insertion of liquid ballast between the dividing device 12 and the wall 11 of the caisson, when this liquid ballast is delivered by pumping over this wall. This liquid ballast is therefore first of all confined by the cells of the dividing device 12 during all the operations while floating, and then, when the caisson is submerged and the filling continues, these cells becoming almost full, the liquid ballast pours into the caisson by the central well 22 which then acts as an overflow.

There is thus a progressive movement of this liquid 20 ballast into the sand ballast 20, followed by its insertion from the top to the bottom between the flexible skirt 30 and the wall 11 of the caisson (see FIG. 9) which ensures automatic detachment of this flexible skirt 30 with respect to the wall 11 of the caisson.

FIGS. 10 and 12 illustrate the application of the invention to the establishment of a fluid-storage reservoir, for example a tank for hydrocarbons.

FIG. 11 illustrates more precisely the submerging 30 phase of the caisson intended to form the reservoir body, this submergence being effected by means of a dividing device 12 according to the invention, which rests on a sand ballast 20, and in which submerged pumps 35 gradually deliver the ballast water.

After submerging (see FIG. 11) the caisson is partly filled with a final sandy ballast 36, passages or drainage channels 37 being provided in the wall 11 of the caisson so as to allow the hydrostatic levels to become balanced as far as possible on each side of this wall.

40 A flexible sealing layer 38 is then placed in position on the sand ballast 36, in co-operation with an annular sealing joint 39, as shown in FIG. 12.

Thus, as can be seen from FIG. 12, air-vents 40 are provided in the wall 11 for the breathing of the sand 45 ballast 36.

The fluid 41 to be stored is put into position directly on the flexible sealing layer 38, so that the storage reservoir 50 thus formed has its wall constituted by the upward extension of the wall 11 of the caisson, and its bottom is formed by the flexible fluid-tight layer 38 placed in position on the sandy ballast of the caisson.

The roof of such a reservoir may be formed, without any particular difficulty, by a conventional floating roof 43 of the same type as those employed on reservoirs 55 built on land.

Furthermore, such a sea or river tank offers the same possibilities of exploitation as a reservoir installed on land. These possibilities are illustrated in FIGS. 11 and

60 13. In this latter figure, there have been shown diagrammatically at 45 the incoming and outgoing pipe conduits, at 46 the service bridges, at 47 a technical construction and at 48 a landing quay.

As shown in FIG. 14, an installation of this kind may 65 serve a number of storage reservoirs 51 of the same type as that described above, these reservoirs being for example arranged substantially in line and eventually forming a dyke.

These reservoirs offer the maximum safety in respect of pollution, since only a major shock can cause a leakage of the stored fluid.

In the case where such reservoirs are effectively required to form a dyke, it may be advantageous to arrange them at a distance from each other in order that their circular shape, combined with the empty spaces between them, can enable the best compromise to be obtained between a small agitation on the sheltered side and an admissible over-elevation on the exposed side.

FIG. 15 illustrates a simplified form of construction of the dividing device 12 according to the invention. This latter is then simply formed by an assembly of inter-crossed walls 55 which are substantially perpendicular to the bottom 10 of the caisson and which plunge into a bed of relatively permeable material 56 arranged on this bottom 10.

In fact, this bed 56 must be made of a sufficiently impermeable material in order that percolation may not be too rapid, especially during the rocking movements of the caisson due to the swell.

The dividing device according to the invention furthermore permits a particular construction of the caisson, in which it is intended to be placed.

This possibility is illustrated in FIGS. 16 to 18; the bottom 10 of the caisson is an apron distinct from the associated wall 11, this wall resting on the bottom on simple supports 60.

These supports are preferably made of anisotropic material capable of transmitting the direct forces, but not their moments. Supports of this kind may be made of hooped synthetic rubber and especially of rubber sold under the Trade name of "NEOPRENE."

According to the form of construction shown in FIG. 16, an annular fluid-tight joint 61, of the WATERSTOP type for example, is associated with the supports 60, a packing of elastic material 62 is inserted between the peripheral edge of the bottom or apron 10 and the wall 11, and the latter is engaged by a shoulder 63 on the bottom or apron 10.

This shoulder may have a section with a circular contour, or a saw-toothed contour as illustrated in FIG. 17.

According to the alternative form shown in FIG. 18, 45 the wall 11 rests simply by its edge on the bottom or apron 10 with the interposition of supports 60 of anisotropic material, these supports being associated with one or more annular fluid-tight joints 61.

FIGS. 19 and 20 relate to an alternative form of construction in which the caisson is provided parallel to its bottom 10 with a polygonal section, for example an octagonal section.

FIG. 21 illustrates a further possibility offered by the invention, especially for the construction of reservoirs of the same type as that described with reference to FIGS. 10 to 12.

According to the form of construction shown in FIG. 21, the wall 11 of the caisson is doubled by a second wall 70 arranged coaxially or eccentrically about the previous wall, the two walls 11 and 70 being associated with the same bottom or apron 10, but being free from any mechanical connection with each other.

The annular space 71 between these two walls can be advantageously employed for placing in position the sand or other ballast at a level which may be different from that of the sand ballast in the internal space.

However this may be, the additional wall 70 provides further protection for the caisson.

It will of course be understood that the present invention is not limited to the forms of construction described and illustrated, but includes any alternative form of construction and/or of combination of their various elements. In all cases, the dividing-up device will preferably be established in such manner as to have a relative deformability with respect to the wall of the caisson such that the pressure of a liquid ballast contained therein is transmitted in a substantially uniform manner to the said wall, or a capacity of movement such that there is practically no transmission of force radially and axially. In this case the partitions may for example be slidably mounted in grooves formed in the wall of the caisson.

What I claim is:

1. An offshore caisson of prestressed reinforced concrete for use in the construction of sea or river works, comprising a sea-worthy structure including a bottom, at least one lateral wall, and means for dividing up liquid ballast in the caisson comprising, in section substantially parallel to the bottom, a cellular structure independent of said wall and said bottom, and means supporting said cellular structure in spaced relation from said wall and said bottom.
2. An offshore caisson as claimed in claim 1, wherein the dividing up means is removable from the rest of the caisson.
3. An offshore caisson as claimed in claim 1, said supporting means comprising a radially deformable system of rolls in lattice formation, said dividing up means bearing against the wall and the bottom of the caisson only through said radially deformable system.
4. An offshore caisson as claimed in claim 1, wherein the dividing up means comprises a plurality of partitions substantially perpendicular to the bottom of the caisson, and a bed of relatively impermeable material on said bottom, said partitions projecting into said bed.
5. An offshore caisson as claimed in claim 1, wherein said dividing up means comprises a plurality of distinct, separable parts.
6. An offshore caisson as claimed in claim 5, further comprising a flat cover strap for holding the upper edges of said parts together in pairs.
7. An offshore caisson as claimed in claim 5, further comprising a central wall, said parts being disposed around the central wall which acts as an overflow device.
8. An offshore caisson as claimed in claim 5, wherein the parts are surrounded by at least one flexible cylindrical skirt, further comprising holding means for exerting said skirt against the lateral wall of the caisson.
9. An offshore caisson as claimed in claim 8, further comprising a first flexible skirt at the top of said dividing up means, and an inflatable tube or roll for urging said flexible skirt against the lateral wall of the caisson.
10. An offshore caisson as claimed in claim 9, further comprising a second flexible skirt at the base of said dividing up means, said second flexible skirt being urged against the lateral wall of the caisson by liquid ballast.
11. An offshore caisson as claimed in claim 1, wherein the lateral wall is cylindrical and is joined to said bottom only by anisotropic means in combination with flexible sealing means.
12. An offshore caisson as claimed in claim 1, in which the lateral wall is covered, over at least part of

its height, by a second wall which is associated also with said bottom and has no mechanical connection with the first lateral wall.

13. An offshore caisson as claimed in claim 1, wherein said dividing up means is relatively deformable with respect to the lateral wall of the caisson so that the pressure of liquid ballast therein is transmitted to the lateral wall in a substantially uniform manner.

14. An offshore caisson as claimed in claim 1, further comprising grooves in the lateral wall, said dividing up means having a plurality of partitions slidably mounted in the grooves.

15. An offshore construction comprising a plurality of offshore caissons as claimed in claim 1.

16. An offshore caisson as claimed in claim 1, for use

15

in the construction of a fluid storage reservoir, wherein said lateral wall of the caisson forms the side wall of the reservoir, further comprising a sandy ballast on said bottom of the caisson and a fluidtight layer supported on the sandy ballast forming the bottom of the reservoir.

17. A breakwater comprising a plurality of caissons according to claim 1 spaced apart from one another.

18. An offshore caisson as claimed in claim 1, in the form of a buoyant vessel, and means for introducing ballast into said vessel to alter the buoyancy thereof.

19. An offshore caisson as claimed in claim 1, wherein said dividing up means comprises a single unitary structure.
